UNITED STATES PATENT OFFICE.

MAX KLEIN, OF NEW YORK, N. Y., ASSIGNOR TO SHAPIRO & ARONSON, INC., OF NEW YORK, N. Y., A CORPORATION OF NEW YORK.

DESIGN FOR A BODY FOR LIGHTING FIXTURES.

Application filed September 2, 1924. Serial No. 10,656. Term of patent 3½ years.

To all whom it may concern:

Be it known that I, MAX KLEIN, a citizen of the United States, residing at New York, in the county of New York and State of New York, have invented a new, original, and ornamental Design for a Body for Lighting Fixtures, of which the following is a specification, reference being had to the accompanying drawing, forming part thereof.

Fig. 1 is a front view of a lighting fixture, showing my new design.

Fig. 2 is a detail view showing the contour of the plate I use in my design to produce the structure shown in Fig. 1. A portion of Fig. 2 is shown in detailed ornamentation, it being understood the unornamented part involves a mere repeat of the completed portion.

I claim:

The ornamental design for a body for lighting fixtures, as shown.

MAX KLEIN.
